UNITED STATES PATENT OFFICE.

LEROY G. GATES, OF BAKERSFIELD, CALIFORNIA, ASSIGNOR TO STANDARD OIL COMPANY, OF SAN FRANCISCO, CALIFORNIA, A CORPORATION OF CALIFORNIA.

APPARATUS FOR PUMPING DEEP WELLS.

Application filed February 25, 1925. Serial No. 11,484.

To all whom it may concern:

Be it known that I, LEROY G. GATES, a citizen of the United States, residing at Bakersfield, in the county of Kern and State 5 of California, have invented certain new and useful Improvements in Apparatus for Pumping Deep Wells, of which the following is a specification.

My invention relates to an apparatus for 10 pumping deep wells and is particularly adapted for pumping wells in which considerable gas is present.

The principal object of my invention is to provide a well pumping apparatus in 15 which the pump and also its driving means, if the latter be associated with the pump in the well, can be pulled to the surface for cleaning or repairing without losing the entire column of pumped fluid which stands above 20 the pump, and without the necessity of pulling the string of tubing which conducts the pumped fluid to the surface.

A further object of my invention is to provide means for the escape of the gases produced in the well, in order to prevent said gases from passing through the pump and interfering with its action. Such conditions are commonly met with in oil wells, and, therefore, my invention is adapted for such 30 use. The separation of the gas and the oil is accomplished by providing a tubing string within the well casing for conducting the pumped oil to the surface, the gas being free to escape through the well outside of 35 said tubing. The oil discharge tubing string remains permanently in the well, and is preferably of a diameter smaller than that of the well casing, but large enough to permit the pumping member to be lowered to 40 its operative position through said tubing.

A separable connection is provided between the pump and the lower end of the discharge tubing string, to permit said pump to be pulled when necessary without disturbing 45 said tubing, and suitable means are provided to retain the column of pumped oil within the discharge tubing when the pump is pulled out, so that said column of oil is not lost back into the well.

As an alternative construction, the discharge tubing string may be of smaller diameter and the pump may be lowered beside instead of inside of said tubing. As 50 in the previously mentioned form of construction, the pump is separably connected with the lower end of the discharge tubing

string, to permit it to be pulled independently of said tubing, and means are provided for retaining the column of pumped oil in the discharge tubing when the pump is 60 pulled.

It will be readily understood that, by the above outlined construction, the pump, whether lowered inside or outside the discharge tubing string, can be pulled at any 65 time for cleaning or repair without removing said tubing string, which remains permanently in the well. This effects a great saving in time and labor over the usual practise of pulling and replacing the entire 70 string of tubing whenever the pump must be repaired or cleaned. The provision for retaining the column of pumped oil in the tubing string when the pump is pulled also effects a considerable saving of time, especially when the large diameter tubing is 75 used and the pump lowered therethrough, for in such cases the amount of oil contained in said tubing is considerable, and, if it were lost back into the well when the 80 pump is pulled, would necessitate running the pump for several days, in deep wells, before the column of pumped oil reached the surface and production started. The use of the tubing string, moreover, prevents 85 trouble from gas by permitting such gas to escape between said tubing and the well casing without interfering with the action of the pump.

A still further object of my invention is 90 to provide means for suitably supporting the tubing string, with its column of pumped oil, and the pump itself, within the well. In comparatively shallow wells the entire weight may be suspended by the tubing 95 string alone, or part of the weight may be supported by the usual slips having frictional engagement with the casing, but in deep wells, and especially when the large diameter tubing is used, the great weight of 100 such tubing and the column of pumped oil would necessitate additional supporting means, and in such cases I provide a supporting column or foot extending from the lower end of the tubing to, and resting upon, 105 the bottom of the well. Obviously, either the slips, or the supporting foot, or both, may be used, and in the latter case I provide means, fully described hereinafter for distributing the weight between the slips 110 and the supporting foot, so that each will bear its proper share.

The pumping member of my apparatus may be of any desired type, and may be operated either by the usual sucker rods from the surface, or may be driven by a suitable motor associated with the pump and lowered with it into the well by a cable or other means of suspension.

The latter type of apparatus is preferable, eliminating the sucker rods, which are not only inefficient in operation, on account of the friction losses involved, but which necessitate much time and labor in pulling the pump.

For purposes of illustration, the motor driven type of pump is indicated in the accompanying drawings, but the details of construction thereof have been omitted, as forming no part of the present invention. It is to be understood moreover, that the form and construction of the apparatus herein shown and described may be varied, within the limits of the claims hereto appended, without departing from the spirit of the invention as set forth in said claims.

With this in view, my invention will now be fully described with reference to the accompanying drawings, wherein—

Fig. 1 is a broken longitudinal section of one form of my well pumping apparatus in operative position in a well, the pumping member thereof being shown partially in elevation.

Fig. 2 is a similar view of a slightly different form of supporting means, the pumping member being removed therefrom.

Fig. 3 is a broken longitudinal section of a modified form of apparatus embodying my invention.

Fig. 4 is a similar view of the fluid supporting member shown in Fig. 3, the pumping member being removed therefrom, and a slightly different weight supporting member being associated therewith.

In the drawings, the reference numeral 1 designates the casing of a well. A string of tubing 2 which, in the form of construction illustrated in Fig. 1, is of only slightly smaller diameter than the well casing 1, is lowered into the well until its lower end extends into the oil. Secured to the lower end of the tubing string 2 is a member 3 which has a preferably central passage 4 extending therethrough. A check valve 5 is provided in said passage.

The reference numeral 6 designates a pump body adapted to be lowered into the tubing string 2 by any suitable means, as, for example, a cable 7. The pump body 6 may be of any desired construction, but for purposes of illustration I have shown a barrel 8 in which a plunger 9 operates. Suction and discharge valves 10 and 11 respectively are provided, the latter being carried in said plunger. The pumped oil passes up through the plunger 9 and a suitably

disposed passage, indicated at 12, and is discharged into the tubing string 2 through a port 13. The plunger 9 is understood to be operated by any suitable mechanism carried within the pump body 6, but as such mechanism forms no part of the present invention, it has been omitted from the drawings.

The lower end of the pump body 6 is provided with a tubular extension 14 forming a suction intake to the barrel 8. Said tubular extension is adapted to fit into the passage 4 of the member 3, and suitable packing 15 is provided in said passage to make a tight joint with said tubular extension 14. A downwardly extending finger 16 is preferably provided upon the lower end of the tubular extension 14 for the purpose of moving the check valve 5 off its seat when the pump body 6 is in its operative position, as shown in Fig. 1.

It will readily be seen that when the pump body 6 is in the position shown in Fig. 1, the oil is drawn up into the barrel 8 through the passage 4 of the member 3 and through the tubular extension 14. However, when the pump body 6 is pulled out of the well for cleaning or repair, the check valve 5, freed by the finger 16, is allowed to seat, as shown in Fig. 2, thereby retaining the entire column of pumped oil within the tubing string 2 and preventing it from flowing back into the well.

The tubular extension 14 is preferably made relatively small in diameter, so as to leave the bottom surface 6^a, Fig. 1, of the pump body 6 as large as possible. This bottom surface 6^a is, of course, exposed to the pressure of the pumped fluid within the tubing string 2, and such pressure, acting upwardly, against said bottom surface 6^a, tends to assist the cable 7 in initially breaking said body away from the tubing bottom member 3, thereby preventing undue strain on said cable. For the same reason, the tubing bottom member 3 is provided upon its upper end with relatively narrow lugs 3^a upon which the bottom 6^a of the pump body 6 rests, so that the fluid pressure may be exerted upwardly against said bottom. Obviously, if the pump body 6 were set tight upon the member 3, the fluid pressure upon the upper end of said body would be so great, in deep wells, as to necessitate a much heavier cable to initially separate said body from the member 3, than would be required to lift said body after such separation.

In deep wells the weight of the tubing string 2 and the column of oil therewithin may render it necessary to support said tubing string 2 in some manner other than by suspension from the surface, and in such cases I may employ a supporting foot 17, which preferably consists of a perforated tube, and which may be secured, as indi-

cated at 18 in Fig. 1, to the lower end of the member 3. The lower end 19 of said foot rests upon the bottom of the well.

The weight of the tubing string 2 with its 5 column of pumped oil, and the pump body 6, may also be partially supported by the usual toothed slips 20, as shown in Fig. 2, which are forced outwardly into engagement with the casing 1 by riding up on inclined surfaces 21. If it is advisable to 10 employ both the slips 20 and the supporting foot 17, I prefer to use the construction shown in Fig. 2. In this construction, the foot 17 is movably associated with the tubing bottom member 3 by means of the sliding connection shown at 22, and a heavy 15 buffer spring 23 is interposed between a shoulder 24 formed upon said foot and the member 3. A lighter spring 25 is interposed 20 between said shoulder and the slips 20, as shown. When, in lowering the apparatus into the well, the foot 17 reaches the well bottom and comes to rest, the heavy spring 25 is compressed by the further downward 25 movement of the member 3, and during such further movement, the lighter spring 25 sets the slips 20 against the casing 1 by moving them upwardly upon their inclined surfaces 21. By properly proportioning the 30 springs 23 and 25, the setting of the slips may be timed to occur when the foot 17, acting through the buffer spring 23, has taken up its pre-determined proportion of the load. By this means, the entire weight 35 may be properly distributed between the slips 20 and the foot 17. The buffer spring 23 also automatically takes care of any expansion or contraction of the parts, or any settling of the foot 17. Obviously, the 40 resilient or buffer spring connection between the tubing bottom member 3 and the foot 17 may be used without the slips 20, in place of the rigid construction shown in Fig. 1.

In the form of construction shown in Fig. 3 of the drawings, the discharge tubing string is indicated by the numeral 2', and is of smaller diameter than that described above. Said tubing string 2', however, is 50 secured at its lower end to a bottom member 3', which constitutes a connection between said tubing string and the pump body 6'. A passage 4' extends vertically through the member 3', but in this form of the apparatus the check valve 5' for retaining the oil column in the discharge tubing string 2' is 55 positioned as shown in a passage 5" connecting the lower end of said tubing string 2' with an annular channel 4" formed in the wall of the vertical passage 4'. The pump body 6' may be supported in any desired manner, not shown.

The pump itself may be constructed in any suitable manner, having both its intake and its discharge at the bottom. For

example, I have shown a barrel 8' in which operates a plunger 9' and which has inlet and discharge valves 10' and 11' respectively. The oil discharged through the valve 11' passes into a chamber 12' surrounding the barrel 8' and communicating with a port 13' adapted to register with the annular channel 4" in the member 3'. A downward extension 14' of the pump body 6' is adapted to fit into the passage 4' of 70 the member 3' and said passage is preferably provided with suitable packing 15' to make a tight joint with said extension 14'. The outlet port 13' is formed in this extension as shown, as is also an intake passage 80 10" leading to the inlet valve 10'.

The member 3' may be supported in the well by any suitable means in addition to being suspended by the discharge tubing string 2'. To indicate any such supporting 85 means I have shown toothed slips 20', Fig. 3, which are understood to engage the casing 1 in a manner similar to that described above, and which may be operated by any suitable means not shown. If desired, a 90 supporting foot 17', as shown in Fig. 4, may be secured, as at 18' to the member 3', said supporting foot having a lower end 19' adapted to rest upon the well bottom.

The operation of the form of apparatus 95 illustrated in Fig. 3 is essentially similar to that of the form shown in Fig. 1. The tubing string 2' and the member 3' are positioned in the well initially and the pump body 6' associated therewith. The operation of the pump causes the oil to be drawn up through the passages 4' and 10" into the barrel 8', and to be discharged through the chamber 12', the port 13', the annular channel 4" and the passage 5" into the tubing string 2'. The pump body 6' may be 100 separated from the member 3' to enable said pump body to be pulled to the surface for cleaning or repair, in which case the check valve 5' retains the column of pumped oil in the tubing string 2' to prevent it from flowing back into the well. 110

It will be seen that in both forms of the apparatus described above, the well casing is not packed off, so that there is a free escape for the natural gases of the well to the surface. In the form illustrated in Fig. 1 said gases pass up between the tubing string 2 and the casing 1, and in the form shown in Fig. 3 they are free to pass up around the pump body 6' and the tubing string 2'. 115

It will also be seen that, in either form, the pump body can be pulled to the surface without disturbing the tubing string and without losing the column of pumped oil contained therein. 120

I claim:—

1. An apparatus for pumping oil wells, 130 comprising a tubing string positioned with-

- in a well and adapted to conduct the pumped oil to the surface, a member connected with the lower end of said tubing string and having a substantially vertically disposed passage therethrough, supporting means carried by said member for releasably gripping the well casing, a pump separably associated with said member and adapted to draw the oil through said passage and to discharge it into said tubing string, and a valve carried by said member for supporting the column of pumped oil within said tubing string when the pump is separated from said member.
5. An apparatus for pumping oil wells, comprising a tubing string adapted to be positioned within the well to convey the pumped oil to the surface, a pump lowerable within said tubing string and separably associated with the lower end thereof, said pump being adapted to discharge the oil into said tubing string, a valve in the lower end of said tubing string for retaining the column of pumped oil within said tubing string when the pump is separated therefrom, and means for holding said valve open when the pump is in operative position.
6. An apparatus for pumping oil wells, comprising a tubing string adapted to be positioned within a well to conduct the pumped oil to the surface, a plug member secured within said tubing string, said plug member having a substantially vertically disposed passage therethrough, spaced lugs rising from the upper end surface of said plug member, a pump lowerable within said tubing string and adapted to rest upon said lugs, a tubular extension upon said pump fitting within said passage, said pump being adapted to draw the oil through said passage and to discharge it into said tubing string, and a valve carried by said plug member for retaining the column of pumped oil within said tubing string when the pump is separated from said plug member.
7. An apparatus for pumping oil wells comprising a tubing string positioned within the well and adapted to conduct the pumped oil to the surface, means associated with said tubing string for gripping the well casing, a support movably associated with said tubing string and extending therefrom to the bottom of the well, means actuated by the relative movement between said tubing string and said support for operating said gripping means, a pump separably associated with the lower end of said tubing string and adapted to discharge the oil thereinto, and means for supporting the column of pumped oil within said tubing string when the pump is separated therefrom.
8. An apparatus for pumping oil wells comprising a tubing string positioned within the well and adapted to conduct the pumped oil to the surface, means associated with said tubing string for gripping the well casing, a support movably associated with said tubing string and extending therefrom to the bottom of the well, a resilient weight-supporting connection between said tubing string and said support, means actuated by the relative movement between said tubing string and said support for operating said gripping means, a pump separably associated with the lower end of said tubing string and adapted to discharge the oil thereinto, and means for supporting the column of pumped oil within said tubing string when the pump is separated therefrom.
9. An apparatus for pumping oil wells comprising a tubing string positioned within the well and adapted to conduct the pumped oil to the surface, a supporting member resiliently connected with the lower end of said tubing string and extending therefrom to the bottom of the well, a pump separably associated with the lower end of said tubing string and adapted to discharge the oil thereinto, and means for supporting the column of oil within said tubing string when the pump is separated therefrom.
10. An apparatus for pumping oil wells comprising a tubing string positioned within the well and adapted to conduct the pumped oil to the surface, means associated with said tubing string for gripping the well casing, a pump separably associated with the lower end of said tubing string and adapted to discharge the oil thereinto, and means for supporting the column of pumped oil within said tubing string when the pump is separated therefrom.
11. An apparatus for pumping oil wells comprising a tubing string positioned within the well and adapted to conduct the pumped oil to the surface, a pump separably associated with the lower end of said tubing string and adapted to discharge the oil thereinto, and means for supporting the column of pumped oil within said tubing string when the pump is separated therefrom.
12. An apparatus for pumping oil wells comprising a tubing string positioned within the well and adapted to conduct the pumped oil to the surface, means associated with said tubing string for gripping the well casing, a pump lowerable within said tubing string and separably associated with the lower end of said tubing string and adapted to discharge the oil thereinto, and means for supporting the column of pumped oil within said tubing string when the pump is separated therefrom.
13. An apparatus for pumping oil wells comprising a tubing string positioned within the well and adapted to conduct the pumped oil to the surface, means associated with said tubing string for gripping the well casing, a support movably associated with said tubing string and extending therefrom to the bottom of the well, means actuated by the relative movement between said tubing string and said support for operating said gripping means, a pump separably associated with the lower end of said tubing string and adapted to discharge the oil thereinto, and means for supporting the column of pumped oil within said tubing string when the pump is separated therefrom.
14. An apparatus for pumping oil wells comprising a tubing string positioned within the well and adapted to conduct the pumped oil to the surface, means associated with said tubing string for gripping the well casing, a support movably associated with said tubing string and extending therefrom to the bottom of the well, a resilient weight-supporting connection between said tubing string and said support, means actuated by the relative movement between said tubing string and said support for operating said gripping means, a pump separably associated with the lower end of said tubing string and adapted to discharge the oil thereinto, and means for supporting the column of pumped oil within said tubing string when the pump is separated therefrom.
15. An apparatus for pumping oil wells comprising a tubing string positioned within the well and adapted to conduct the pumped oil to the surface, means associated with said tubing string for gripping the well casing, a support movably associated with said tubing string and extending therefrom to the bottom of the well, a resilient weight-supporting connection between said tubing string and said support, means actuated by the relative movement between said tubing string and said support for operating said gripping means, a pump separably associated with the lower end of said tubing string and adapted to discharge the oil thereinto, and means for supporting the column of pumped oil within said tubing string when the pump is separated therefrom.

In testimony whereof I have signed my name to this specification.

LEROY G. GATES.
